(57) CLAIM

The ornamental design for a hair accessory with multiple clips, as shown and described.

DESCRIPTION

FIG. 1 is a front elevation view of a hair accessory with multiple clips showing my new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a perspective view of the hair accessory of FIG. 1 with the clips in an open position.

The boundaries shown in broken lines are for illustrative purposes only and do not form part of the claimed design.
